(57) **CLAIM**

I claim the ornamental design for a lighting device, as shown and described.

DESCRIPTION

FIG. 1 is a perspective view of a lighting device, as viewed from the top and one side thereof.

FIG. 2 is a side elevation view of the lighting device of FIG. 1, the other side being a mirror image thereof.

FIG. 3 is a top plan view of the lighting device of FIG. 1; and, FIG. 4 is a bottom plan view of the lighting device of FIG. 1. The details shown in broken lines are for illustrative purposes only and form no part of the claimed design.
